WALTER G. BARBOUR, OF QUINCY, MASSACHUSETTS, ASSIGNOR TO PERLEY E. BARBOUR, OF QUINCY, MASSACHUSETTS, DOING BUSINESS AS BARBOUR WELTING COMPANY, OF BROCKTON, MASSACHUSETTS

METHOD OF MAKING WELTING

Application filed August 2, 1930. Serial No. 472,722.

My invention relates to shoe welting and is especially concerned with the preparation of fillets and strips in the form of stitch-down welting although its use may be extended to the lighter weights of Goodyear and other welting varieties.

The object of my invention is to utilize all portions of the leather stock without waste and to produce welting from ungrained stock of substantial equal quality to that obtained from grain-faced stock.

To the accomplishment of this object my invention consists in the novel processes and method of manufacture hereinafter described.

15 A better understanding of the invention will be had by reference to the two somewhat exaggerated perspective views of the accompanying drawing illustrative of the steps employed in practising my method in which 20 Figure 1 shows the step of splitting a grain ribbon from an unlimited long fillet which has the natural grain of the stock on one face; and Fig. 2 shows an unlimited long roll of grain ribbon in process of being 25 cured to an ungrained fillet in this instance cut wholly from the flesh of the stock.

The grain fillet indicated by 10 (Fig. 1) is formed by the usual method, that is, after the shoulder or other portion of the hide has 30 been stripped these strips are scarfed and joined and this unlimited long hide fillet is evened and then split widthwise into a grain fillet, such as 10, and a flesh fillet. The thickness or substance of the grain fillet thus produced may vary but for use as stitchdown 35 welting it may be substantially 2/32 of an inch. The thickness of the unlimited long hide fillet is more generally about 1/8 of an inch, although it varies from this, which 40 when split to obtain the grain fillet 10 will yield also a flesh fillet of substantially the same substance, i. e. 2/32 of an inch. In practising my method I work one grain fillet and one flesh fillet to produce two grain fillets.

45 It is the usual practice to skive the grain

fillets, removing a thin grain ribbon 12 of substantially paper thickness incorporating the shelly outer surface of the grain. This step is illustrated by Fig. 1 leaving a grain fillet 14 having a grain face from which the 50 harder and less flexible outer surface has been removed. The grain ribbon 12 is wound on the spindle 15 of a reel, conveniently as it is split, and is used in these unlimited long strips in the second step of my method. I 55 now feed a flesh or any ungrained fillet 16 (Fig. 2) through a suitable guide, having first cemented the side which faces upward while in the guide, and support the roll of 60 grain ribbon 12 in position to be fed forward with the ungrained fillet and be pressed upon its cemented face. I prefer to use latex cement which provides a bond of great strength and permits the paper-like grain ribbon to 65 lie smoothly adhered over the entire area of the fillet face to which it is applied.

I thus produce a composite fillet 18 or strip useful for stitchdown and other welting, in unlimited long lengths which consists, in the illustrated example, of a fillet 16 cut wholly 70 from the flesh but yet having a grain face making it the substantial equivalent of the grain fillet 14. The hide fillet, when prepared for the manufacture of stitchdown welting, is of such width that a multiple 75 number of stitchdown strips are obtained by cutting either fillet 14 or 18 longitudinally by parallel spaced cuts but my method is applicable to any width of fillet and even to a strip for a single stitchdown welt.

80 After the grain ribbon 12 has been removed to produce the grain fillet 14 the skived face thereof is redressed and reprocessed to provide the desired surface and color. Either the inner or outer face of the ribbon may be cemented to the flesh fillet. When the ribbon is applied with its outer shelly face outward I may skive the grain face of the composite fillet 18 removing only an extremely 85 light portion comprising the shelly outer 90

face from the surface of the grain ribbon 12 exposing a more flexible grain surface which can be re-colored and redressed in any desired manner. This final step is not illustrated since Fig. 1 illustrates the same method of skiving a thin ribbon from a face of a fillet.

I specifically do not confine myself to any particular width or thickness of leather 10 with which to work in carrying out my invention. Factory processes yield both grain ribbons and flesh strips in unlimited long lengths and of varying widths and by matching widths all can be used. Thus my method 15 not only produces welting that has better wearing qualities and a better appearance but it also saves valuable stock that otherwise would be classed as waste.

In some of my claims I have referred to 20 the securing of an unlimited long thin grain ribbon to one face of an unlimited long ungrained fillet. I do not mean thereby to limit my invention to the use of an ungrained fillet made of a single splitting of leather 25 because obviously such ungrained fillet may be made of several splittings cemented together to obtain a fillet of the desired thickness, and the term "an ungrained fillet" is inclusive of both kinds. The important feature 30 of my invention is the transformation of an ungrained fillet, however prepared, into a grain fillet by applying thereto an unlimited long grain ribbon, the exact nature of the body of the resultant welting being immaterial except as it affects the quality of the 35 final product.

The nature and scope of my invention having been indicated and the manner of practicing my method having been described, what 40 is claimed as new is:—

1. The method of making composite welding fillets and strips which comprises removing an unlimited long thin grain ribbon from the face of an unlimited long grain 45 fillet and then securing this ribbon as a progressive process to one face of an unlimited long ungrained fillet.

2. The method of making composite welding fillets and strips which comprises removing an unlimited long thin grain ribbon from the face of an unlimited long grain fillet, rolling said ribbon on a reel, and then unreeling said ribbon and pressing it progressively upon a cemented face of an unlimited long ungrained fillet fed forward in timed relation to the advance of said ribbon.

3. The method of making composite welding which consists in forming an unlimited long hide fillet by scarfing and joining strips 60 cut from the hide, splitting said hide fillet widthwise to produce an unlimited long grain fillet and an unlimited long flesh fillet, stripping an unlimited long paper-like grain ribbon from the grain fillet, and securing said 65 grain ribbon to one face of the flesh fillet.

4. The method of making composite welding fillets and strips which comprises removing a thin ribbon, which incorporates the shelly outer surface of the grain, from the face of an unlimited long grain fillet, securing this ribbon, shelly face outward, to one face of an unlimited long ungrained fillet, and then lightly skiving the grain face of this composite fillet to remove just the shelly face from the applied grain ribbon.

In testimony whereof I affix my signature.

WALTER G. BARBOUR.
